UNITED STATES PATENT OFFICE.

EDWARD M. WALKER, OF TROY, AND RANSOM D. VIELE, OF ROCKTON, NEW YORK, ASSIGNEES OF ONE-THIRD TO THEODORE D. ROBINSON, OF ALBANY, NEW YORK.

FOLDING-MACHINE.

SPECIFICATION forming part of Letters Patent No. 664,912, dated January 1, 1901.

Application filed June 15, 1899. Serial No. 720,730. (No model.)

To all whom it may concern:

Be it known that we, EDWARD M. WALKER, residing at Troy, county of Rensselaer, and RANSOM D. VIELE, residing at Rockton, county of Montgomery, State of New York, citizens of the United States, have invented certain new and useful Improvements in Folding-Machines, of which the following is a specification.

10 The invention relates to such improvements; and it consists of the novel construction and combination of parts hereinafter described and subsequently claimed.

Reference may be had to the accompanying drawings, and the letters of reference marked thereon, which form a part of this specification.

Similar letters refer to similar parts in the several figures.

20 Figure 1 of the drawings is a view in front elevation of our improved folding-machine. Fig. 2 is an end elevation of the same. Fig. 2^a is a view on an enlarged scale of a portion of the folder-plate shown complete in Fig. 8, portions of the plate being broken away and the adjustable corner-block being removed. Fig. 2^b is a similar view with the adjustable corner-block restored, showing the same in one of its positions in solid lines and in its other position in dotted lines. Fig. 3 is a central vertical longitudinal section of the same, taken on the broken line 3 3 in Fig. 2, the upper portion of the carriage and the lower portion of the frame being omitted. Fig. 4

30 is a view, partly in plan and partly in transverse horizontal section, on the broken line 4 4 in Fig. 1. Fig. 5 is a plan view of the top of the frame or body of the machine, the carriage being removed. Fig. 6 is a similar view showing the carriage in horizontal section and a plan view of the cam for operating the carriage. Fig. 7 is a transverse section of the main driving-shaft, showing a view in elevation of the intermittent clutch

40 mechanism. Fig. 8 is a bottom plan view of the folder-plate detached. Fig. 9 is a central vertical transverse section of the former, former-stem, and slideway for the stem, showing the cam mechanism for operating the

blank receiving and delivering tray. Fig. 50 10 is a side view of one of the stripper-pins and its supporting slotted plate. Fig. 11 is a bottom plan view of the same.

Our invention relates to folding-machines for inturning the edges of blanks of various 55 forms, as fabric-blanks, in the manufacture of collars and cuffs.

Referring to the drawings, A is the frame of the machine, having the top A' provided with a central aperture or well A². At the 60 bottom of the well is a platform A³, supported from the top by means of the depending rods A⁴. This platform supports upon suitable trackways a carriage B, located within the well and capable of a universal movement 65 within the well and upon said platform. To permit such universal movement, the carriage is mounted directly upon the track-plates B', having longitudinal trackways B², which fit 70 grooves formed in the bottom of the carriage and guide the carriage in its movements in one direction, and these track-plates are in turn mounted upon the trackways B³, formed upon the upper side of the platform A³, extending at right angles to the ways upon the 75 track-plates and fitting grooves formed in the under sides of said plates. The carriage is provided with a top B⁴, which forms the bed or table for the folding operation. The carriage is also provided with uprights B⁵, 80 connected by a framework B⁶ above the bed, which framework contains a slideway B⁷, extending at right angles to the bed and adapted to receive and form a guideway for the stem C, which supports and carries the former 85 or die C', attached to the lower end of the stem. The former-stem is provided with a plate-gear C², adapted to be engaged by a gear-segment C³, rotatively mounted upon the framework B⁶ and adapted to be rotated 90 by means of the crank-handle C⁴, whereby reciprocating vertical movements can be imparted to the stem to move the former toward and from the bed. A spring-actuated rod C⁵ engages the former-stem and tends to yieldingly support the same in either an elevated, 95 lowered, or intermediate position in the slide-way.

D is the folder-plate, which extends across the well in the top of the machine and has its ends connected with said top, as by studs or pins D', projecting from said top and fitting 5 suitable apertures D², formed in the folder-plate, whereby the folder-plate is maintained in fixed relation to the frame of the machine. The folder-plate is adapted to rest upon the bed of the carriage normally, the bed and 10 former being capable of a movement in unison with each other and with the carriage relatively to the frame of the machine and the folder-plate fixed thereto.

In accomplishing the folding operation a 15 blank slightly larger than the desired size of the finished blank is employed and is laid upon a central aperture D³ in the folder-plate and forced down through such aperture upon the bed of the carriage by lowering the former 20 thereupon, the former being of the exact shape which it is desired to impart to the finished blank and the folder-aperture being of similar shape and closely approximating the size of the former, so that as the blank is 25 forced down through the folder-aperture its side edges will be bent upwardly by engagement with the walls of the aperture into a position at right angles to the body of the blank. While the blank is thus held tightly clamped 30 between the former and bed and with its edges upturned, a universal movement is imparted to the carriage upon its ways, as will be hereinafter more particularly described, causing the several edges of the blank and 35 former to slide beneath and be overlapped by the folder-plate successively, thereby crushing the upturned edges of the blank down upon the former and causing the blank to assume a folded form similar to that of the 40 former. At the end of its universal movement the carriage is returned to its original normal position, which locates the former centrally of the folder-aperture, and the former, with the blank folded thereon, is raised and 45 the blank removed in any known manner.

As a means for imparting a universal movement to the carriage upon its ways we provide a cam E, fixed upon the upper end of a vertical shaft or spindle E', rotatively supported in bearings in the frame of the machine, and adapted to engage the cam-followers E², fixed upon the carriage. We have shown four of these followers in the form of rollers mounted upon brackets E³, adjustably 50 secured to the bottom of the carriage at points equidistant from the center thereof and at an angular distance apart of ninety degrees. By having the four followers so arranged and adapted to all simultaneously engage the cam 55 we are able to exactly center the carriage in the well after each folding operation, thus bringing the former to the center of the folder-aperture in position to be freely raised from the bed.

60 65 We have shown in the drawings a cam having two cam projections E⁴ and two cam depressions E⁵, each projection being located

diametrically opposite one of said depressions, whereby a half-rotation of the cam will produce a universal movement of the carriage, 70 and consequently of the former, causing the said former to be overlapped by the folder on all sides successively.

As a means for operating the cam-shaft E' we provide the same with a beveled gear E⁶, 75 adapted to mesh with a similar gear E⁷ on the horizontal driving-shaft E⁸. The driving mechanism for this drive-shaft consists of the belt-pulley F, supported on the outer end thereof and rotary thereon and connected 80 with said shaft by an intermittent clutch mechanism comprising a dog F', pivoted to the hub F², fixed upon the shaft E', and actuated by the spring F³ to engage the internally-toothed rim F⁴ of the belt-pulley, whereby the 85 hub and shaft are connected with and driven by said-pulley.

The clutch mechanism is automatically disconnected at the end of each rotation of the drive-shaft by means of the stop-rod F⁵, adapted to slide in bearings supported by the frame of the machine and which is projected into the path of said dog by means of the spring F⁶, the dog immediately upon engaging said stop being thrown out of engagement with the 90 toothed rim of the drive-pulley, and thereby disconnecting said shaft and pulley. This stop is moved out of the path of the dog to release the same by means of the angle-lever F⁷, operated by the treadle F⁸ and connecting-link F⁹. When the stop is thus removed, the dog is at once forced by its actuating-spring into engagement with the toothed rim of the drive-pulley, and the resultant operation of the drive-shaft is continued until the 95 dog again engages the stop. The diameter of the beveled gear on the cam-shaft is double that of the intermeshing beveled gear on the drive-shaft, whereby a complete rotation of the drive-shaft imparts to the cam-shaft only 100 a half-rotation, which accomplishes the universal movement of the carriage, as above described.

When the weight of the folder-plate itself is insufficient to exert the desired amount of 115 pressure upon the folded edges of the blank, additional pressure may be secured in any known manner, as by the presser-plates G G, which are forced into engagement with the ends of the folder-plate, respectively, by the 120 spring-actuated rods G' G', each of which passes down through an apertured lug G² on the frame of the machine and is inclosed by a coil-spring G³, which bears at its upper end upon said lug and at its lower end upon 125 a nut G⁴, screwed upon the lower threaded end of said rod, whereby the force of the spring may be varied as desired to produce different degrees of pressure upon the folder-plate.

130 When desired, the bed of the carriage may be heated in any known manner, as by the gas-burners H, projecting upwardly from the supply-pipes H' through apertures in the

platform A³ and bottom of the carriage. When such burners are employed, the carriage is preferably provided with a horizontal diaphragm H², located a short distance beneath and extending parallel with the bed B⁴, whereby an inclosed air-chamber H³ is formed between the diaphragm and bed, which prevents direct contact of the flame from the burners with the bed and causes the 10 heat to be uniformly distributed to the bed.

We have also shown in the drawings of our improved machine mechanism for automatically stripping the folded blanks from the former and delivering them to a table or other 15 receptacle. The stripping mechanism comprises one or more stripping-pins J, each depending from the upper framework B⁶ of the carriage into the path of the former, which is provided with apertures J', adapted to receive the respective pins. As the former is raised from the bed with a blank folded thereon these pins engage the blank through the apertures in the former, and as the upward movement of the former is continued the 20 blank is forced off from the former. The stripper-pins are each adjustably secured to the framework B⁶ by means of a slotted link J² and a screw-bolt J³, inserted through the slot J⁴ of the link and secured to the lower part 25 of said framework B⁶ by means of the nut J⁵. By loosening said nut the link may be adjusted to bring the pin into proper position to enter the aperture in the former. Any desired 30 number of stripper-pins may be employed arranged to enter, respectively, a like number of apertures in the former.

The delivering mechanism comprises, preferably, a tray K, provided on its rear side with a pair of oppositely-projecting trunnions K', adapted to rest and slide upon the downwardly and rearwardly curved ways K², supported by the framework B⁶, and on its front side with a pair of oppositely-projecting trunnions K³, each having a bearing-support in 45 the lower end of an arm K⁴, fixed upon and depending from the rock-shaft K⁵, supported in bearings on the framework B⁶. This rock-shaft is also provided with a short arm K⁶, fixed thereon, and provided on its outer end 50 with a cam-follower K⁷, adapted to travel in a cam-groove K⁸, formed in a cam-plate K⁹, fixed upon and adapted to move with the former-stem C. This cam-groove is so formed that at approximately the same time that the strip- 55 pers are brought into engagement with the folded blank on the former the rock-shaft is operated to move the tray K into position beneath the elevated former to receive the stripped blank as the same falls by gravity 60 after being forced off from the former and that during the first part of the descending movement of the former the rock-shaft will be operated to move the tray rearwardly out of the path of the descending former, which 65 rearward movement causes the front edge of the tray to be slightly elevated, while its rear edge descends upon the curved ways K² un-

til the blank slides by gravity off from the tray and falls upon a table K¹⁰ or other receptacle which may be provided to receive it. 70

Any known mechanisms may be employed for imparting the desired movements to the several parts of our improved machine.

The former and folder of our improved machine are preferably each a rigid unitary construction as regards their movements. 75

In using our improved machine for folding blanks of rectangular form in whole or part the blanks can be folded so that their folded edges will interlock those of one blank with 80 those of another when assembled to form a collar or cuff by folding first the side edges and then the end edges of one set of blanks and folding first the end edges and then the side edges of the other set of complementary 85 blanks, the proper movements of the carriage to produce these results being easily accomplished by substituting different forms of cam in place of the cam E. When so producing a fold on the corner of the blank, it is desirable 90 to provide a recess in the adjacent folder-wall, which extends at an angle to the edge of the blank first folded, to receive the fullness of fabric formed by the fold at the corner of the blank. To adapt the folder of our improved 95 machine to fold the corners of the blanks in this manner, we cut away a portion of the folder adjacent to the corner of the folder-aperture and remove also a small portion of the aperture-wall on each side of the corner, 100 and in the space thus formed we place an adjustable corner-block P, somewhat smaller than such space and secured to the body of the folder by a screw P'. This corner-block is adapted to be adjustably secured in contiguity with the wall of the folder-aperture 105 on either side of the corner and when so secured leaves a small space between the block and wall on the other side of the corner. By loosening the screw P' and changing the adjustment of the corner-block the folder can 110 be adapted for folding either the side before the end or the end before the side of the corner of a blank, as may be desired. A similar block may be provided for each corner, if desired. 115

It is essential that some means be provided for guiding the carriage, with its bed and former, into a predetermined fixed lateral relation to the folder at the conclusion of each 120 folding operation, whereby the folder and former shall be so centered and arranged relatively to one another that the former can be moved toward and from the bed without interference from the folder. We have shown 125 such means in the four cam-followers E², above described, whereby the former is positively and uniformly positioned at the conclusion of each folding operation.

What we claim as new, and desire to secure 130 by Letters Patent, is—

1. In a folding-machine, the combination with a stationary support; of a carriage movably mounted upon said support and capable

- of universal movement in a horizontal plane thereon; a bed and former mounted upon said carriage and movable therewith; a stationary folder connected with said support; and co-
operative with said bed and former; and a cam for imparting to the carriage a universal movement in a horizontal plane, substantially as described.
2. The combination in a folding-machine, of a bed; a unitary rigid former superposed upon the bed and having oppositely-disposed forming edges; means for moving said former toward and from the bed; a unitary rigid folder having oppositely-disposed folding edges co-operative successively with the oppositely-disposed forming edges respectively of the unitary rigid former; means for imparting to one of said unitary members a relative movement, whereby the folding edges are caused to overlap the forming edges successively; and automatically-operating mechanism for guiding into predetermined fixed lateral relation to each other at the conclusion of each folding operation the two unitary constructions and positively maintaining said fixed lateral relation of the parts during the movement of the former toward and from the bed, substantially as described.
3. In a folding-machine, the combination with a stationary support; of a carriage mounted upon said support and capable of universal movement in a single plane thereon; a bed and former mounted upon said carriage and movable therewith; a rigid unitary folder inclosing the former on all sides and connected with said support; means for imparting to the carriage movements successively in different directions in the same plane, whereby the folder is caused to overlap all sides of the former, successively, and means for guiding into predetermined, fixed, lateral relation to each other at the conclusion of each folding operation, the former and folder, substantially as described.
4. In a folding-machine, the combination with a support; and a folder connected with said support; of a carriage movable upon said support; a bed fixed upon said carriage; a slideway supported by uprights erected from said carriage; a former; a stem connected with and supporting said former and movable in said slideway; means for reciprocating the former-supporting stem in said slideway; and means for moving said carriage, and guiding into predetermined, fixed, lateral relation to each other at the conclusion of each folding operation, the former and folder, substantially as described.
5. In a folding-machine the combination with a support; and a folder connected with said support; of a carriage movable upon

said support; a bed fixed upon said carriage; a slideway supported by uprights erected from said carriage; a former; a stem connected with and supporting said former and movable in said slideway; means for reciprocating the former-supporting stem in said slideway; cam-followers on the carriage; a rotary cam engageable with said followers and means for rotating said cam whereby the carriage is operated to produce a co-operative folding movement of the former relatively to the folder and is positively and uniformly positioned at the conclusion of each folding operation, substantially as described.

6. In a folding-machine, the combination with a bed; a former; and folding mechanism; of an automatic stripper for removing folded blanks from the former; a delivering mechanism to receive the blank from the former and deliver the same upon a table or support provided therefor, and means for operating the said delivering mechanism, substantially as described.

7. In a folding-machine, the combination with a bed; a former movable toward and from the bed; and folding mechanism; of stripping mechanism for removing the folded blanks from the former; a blank-receiving tray; means for moving said tray into position beneath the former to receive the stripped blank; and means for moving said tray out of the path of the former, substantially as described.

8. In a folding-machine, the combination with a bed; a former movable toward and from the bed; and folding mechanism; of stripping mechanism for removing folded blanks from the former; a movable blank receiving and delivering tray; means for moving the former toward and from the bed; and cam connections between the former and tray, whereby the tray is moved into position to receive the stripped blank and out of the path of the former in unison with the movements of the former, substantially as described.

9. In a folding-machine, the combination with a folder-plate having an angular aperture and a recess at a corner of said aperture; of an adjustable corner-block secured in said recess and adapted to be secured in contiguity with either a side wall or an end wall of said aperture, substantially as and for the purpose set forth.

In witness whereof we have hereunto set our hands this 27th day of May, 1899.

EDWARD M. WALKER.
RANSOM D. VIELE.
